UNITED STATES PATENT OFFICE.

WALTER WATSON ARNOLD, OF DAWSON, NEW MEXICO.

MEANS FOR PREVENTING DAYLIGHT BANK-ROBBERIES.

1,258,297.

Specification of Letters Patent.

Patented Mar. 5, 1918.

Application filed July 13, 1915. Serial No. 39,711.

To all whom it may concern:

Be it known that I, WALTER W. ARNOLD, a citizen of the United States, residing at Dawson, county of Colfax, and State of New Mexico, have invented certain new and useful Improvements in Means for Preventing Daylight Bank-Robberies; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in means for preventing daylight bank robberies, my object being to provide a construction of such character that as soon as the bank official is made aware of the presence of a would-be robber, he may by a simple movement of the foot or hand cause armor plates of steel or other suitable material, to move into position whereby he will be completely incased by bullet proof walls. As illustrated in the drawing the side walls or partitions of the cage occupied by the official are stationary and made of metal. These may have openings or not as may be desired. If they have openings or relatively small windows through which papers may be passed from one cage to another, provision may be made for automatically closing these openings at the same time that the movable armor plate is actuated or caused to assume its protective position. As illustrated the movable armor plate is located in front only, however, it will be understood that side plates and even a rear plate may be operated in the same manner and on the same principle. In the drawing I have shown no provision for closing the cage in the rear. This, however, may be provided for if desired. The principal idea of the invention consists in a construction whereby protecting plates or partitions, may automatically move into position and afford complete protection to the official against the would-be burglar, these protecting plates or members being normally held inactive and in concealment but are so connected that they may be released at any moment, in which event they will be quickly moved into a protecting position, through the instrumentality of a weight or spring or any other suitable motive power.

Having briefly outlined my present improvement as well as the function it is intended to perform I will proceed to describe the same in detail, reference being made to the accompanying drawing in which is illustrated an embodiment thereof. In this drawing—

Figure 1 is a vertical section taken through a cage of a bank equipped with my improvement.

Fig. 2 is a section similar to Fig. 1, but showing the automatically adjustable armor plate raised to the protecting position.

Fig. 3 is a horizontal section taken on the line 3—3 Fig. 2 looking downwardly.

Referring to the drawing, the numeral 5 designates the desk of the bank official as paying teller, and 6 the opening or window in front of the desk and in front of which the customer stands. In this connection it is assumed that the side walls 7 at the opposite ends of the desk or on the opposite sides of the teller when standing at the desk, are composed of stationary steel plates provided with openings 9 communicating with the cages on opposite sides. The cage is normally provided with the ordinary screen or vertically disposed bars 10 in front and above the window 6 in order to afford the necessary light. The cage is also open at the top through which light may be received if desired.

An adjustable plate 12 which is to close the upper part of the cage in front, that is to say the part of the cage above the desk of the teller, is normally concealed within the casing below the top of the desk and in the rear of the stationary casing member 13. With the lower extremity of this plate is connected as shown at 14, a cable 15 which passes over a pulley 16 just below the top of the desk and thence downwardly underneath a second pulley 17 and thence upwardly, where it is secured to a suitable stationary member 18 which is attached to the desk underneath. Secured to the pulley 17 is a depending rod 19 to which a sectional weight 20 is applied. As many sections or members may be placed upon the rod as desired, these sections being perforated to receive the rod, a nut 21 being employed as a support to hold them in place. The rod of course may be made of any desired length.

When the device is not in use, a trigger 22 passes through one of a pair of vertical guides 23 and engages the lowermost sec-

tion of the weight. This trigger is connected with an arm 24 of a bell crank lever 25, the other arm of the lever being connected as shown at 26 with a rod or cable 27 whose opposite extremity is connected as shown at 28 with a foot lever 29 which is fulcrumed at 30 and equipped at its outer extremity with a foot plate 31.

Each of the side openings 9 of the walls 10 7 of the cage are adapted to be closed by a steel member 32 which is pivoted above the opening as shown at 33 and provided with a rigid arm 34, one extremity of which protrudes as shown at 35 into the path of the plate 12 as the latter moves upwardly, whereby the closure 32 will then be thrown into the position shown in Fig. 2, since the plate 12 as it moves upwardly, will act upon the arm 34 to produce this result. The pivotal joint between the plates 32 and the walls 7 is sufficiently tight to retain the said plates in the raised position, but at the same time will permit the plates to be moved when desired.

From the foregoing explanation, it will be understood that in the event that a robber attempts to hold up the teller, as the latter throws up his hands, one of his feet may press upon the plate 31 of the lever 29, sufficiently to release the weight 20 which will instantly move downwardly, and shoot the steel plate upwardly to the dotted line position in Fig. 1 and into the full line position in Fig. 2. At the same time, the closures 32 will be moved to close the openings 9 in the sides of the cage, thus completely shutting in the teller in front and at both sides.

The upper extremity of the pocket or cavity in which the plate 12 is located is nor-

mally closed by a pivoted cover 36 which 40 overlaps a narrow ledge 37 at the outer edge of the desk 5. Of course, as the armor plate moves upwardly it will raise the cover 36. Attention is also called to the fact that the trigger 22, together with the bell crank lever 45 25 is normally held in the weight-supporting position by a leaf spring 38. As the lever 25 is actuated this spring yields to allow the trigger to move outwardly far enough to release the weight.

Having thus described my invention, what I claim is,—

An apparatus of the class described including a stationary frame work, a plate movably mounted in said frame work, a cable having one extremity connected with the lower part of said plate and its opposite extremity with a stationary support, a pulley which the said cable engages intermediate its extremities, a rod suspended from the 55 pulley, a weight supported by the said rod, a guide-way for the said weight, a bell crank fulcrumed exteriorly on the guide-way, one arm of which is provided with a projection adapted to enter a perforation in 60 said guide-way and engage the weight for holding the latter in the raised position, and means connected with the other arm of the bell crank lever for withdrawing the said projection and releasing the weight when 65 desired.

In testimony whereof I affix my signature in presence of two witnesses.

WALTER WATSON ARNOLD.
